UNITED STATES PATENT OFFICE.

GEORG MÜLLER, OF SCHWÄBISCH-GMÜND, GERMANY.

SELF-CLOSING WATER-COCK WITH DEVICE TO PREVENT BURSTING BY FROST.

937,629.

Specification of Letters Patent. Patented Oct. 19, 1909.

Application filed April 5, 1906. Serial No. 310,010.

To all whom it may concern:

Be it known that I, GEORG MÜLLER, a technologist, and a subject of the King of Würtemberg, and a resident of 65 Lederstrasse, in the city of Schwäbisch-Gmünd, Kingdom of Würtemberg, part of the German Empire, have invented a certain new and useful Improved Self-Closing Water-Cock with Device to Prevent Bursting by Frost, of which the following is a specification.

The present invention is an improved water tap or cock having a valve adapted to close automatically under the pressure of the water supply, and which can be opened to any desired extent by means of a screw spindle. The valve and its casing can be easily separated from the body so that the operative parts of the valve can be easily repaired. The valve casing is provided above the valve seat with channels through which the water flows into the body and out when the valve is open. In the event of the water supply to the cock being stopped and the pressure upon the valve ceasing, the latter will automatically open sufficiently to permit the passage of air and the escape of the water contained in the pipe through a drain cock suitably placed at the lowest point of the pipe.

The accompanying drawings illustrate a cock embodying the present invention, Figures 1 and 2 representing the cock in vertical section and showing the valve in two different positions; and Fig. 3 shows a slight modification of the cock body.

The cock may be constructed in the well known manner and has a body of any desired form having an inlet *a* and outlet *b*, separated by a partition *x* in which is an opening around the exit end of which is an annular packing *i*. Above this opening the body has an internally threaded nipple *y* through which the valve casing *z* is introduced into the body. Said casing has an outer head *c* provided with a threaded portion engaging the nipple *y* and a packing *c'* is interposed between head *c* and nipple *y* to make a water-tight joint therebetween. The lower or inner part of the casing *z* is cylindric and is adapted to impinge upon the packing *i* as shown, and form a water-tight joint between the inner end of the valve casing and the partition *x*; thus forming, within the body, a closed valve-chamber which communicates with the inlet *a*

through the opening in partition *x*. Above chamber *h* the valve-casing has an axial bore *e*, the upper part of which is threaded for the engagement of the spindle *d*, which has a hand-piece *d'*, and may be packed by a stuffing box *d''* as usual. From bore *e* above chamber *h*, radiate apertures *p* through which water can escape to the discharge outlet *b*, when the valve is open.

The valve *n* is adapted to move within chamber *h* and has an extension *o* depending through the opening in partition *x*, and it also has a short stem *f* extending into the bore *e*; said stem is preferably formed separate from the valve, and screwed thereto as shown, and a washer *m* is thereby fastened to the upper end of the valve, and is adapted to seat against the upper end of chamber *h* when the valve is closed, as shown in Figs. 1 and 3, in which position the valve is closed, and no water can pass from chamber *h* into bore *e*.

The stem *f* has a slot *k* in one side, into which projects the end of a screw *l* tapped through the casing, said slot allows the valve to close, under the pressure of the water, and to be opened by manipulation of spindle *d*. Or if the water supply fails, the valve can open by gravity, or drop to the position shown in Fig. 2, screw *l* arresting the descent of the valve and preventing it fully seating upon the packing *i*, and air can pass into the inlet *a* and pipes connected therewith.

When the spindle *d* is in the position shown in Fig. 1, the valve is pressed against its upper seat by the water pressure acting upon the bore *o* and the part *n*. When the valve is opened by screwing down the spindle, the water flows from the inlet *a* through the space left between the edge of the valve *n* and the walls of chamber *h* into bore *o* and then through the perforations *p* to the outlet *b*. The amount of water flowing through the cock can be controlled at will by screwing down the spindle *d* influencing the projection *f*.

The mechanism is so constructed that in the lowest position of the valve (see Fig. 2) the water passage is not entirely shut and air can pass into part *a* as described. Because of the union of the valve body *g* with the valve casing *z*, both the said parts can be put in or removed from the body of the cock for repairs, without disturbing the cock body, and in consequence of the special ar-

angement of the valve upon the shutting off of the water supply the inlet *a* remains in connection with the outer air so that the water remaining in the pipe can be drained off to prevent it freezing.

The modification of body illustrated in Fig. 3 is a known form of body especially adapted for water pipe taps, but the features of the invention do not differ essentially 10 in regard to its construction and mode of working from what has been already described.

Having thus described the invention and in what manner the same is to be performed, 15 I declare that what I claim is:

1. In combination, a body having an inlet an outlet and an intermediate partition with an opening, a valve casing screwed into the body opposite the partition and having its 20 inner end seated on the said partition and containing a valve chamber communicating with said opening and having a bore above said chamber and a passage communicating with the outlet, a valve in said casing adapted to seat against the upper end of said chamber, a guide pin attached to said valve and extending into the bore, means engaging said guide pin to limit the opening movement of the valve, and means for opening said valve against the pressure of the 25 water.

2. In combination, a body having an inlet an outlet and an intermediate partition provided with an opening, a packing ring 30 around the upper edge of this opening, a valve casing screwed into the body opposite the partition and having a hollow inner end seated upon the said packing and

forming a valve chamber, said casing having a passage leading from said chamber above the valve seat and communicating with the outlet, a valve in said casing depending through the partition, a washer on the upper end of said valve adapted to seat against the upper end of said chamber, a 40 guide pin attached to said valve, means engaging said guide pin to limit the opening movement of the valve, and means for opening said valve against the pressure of the 45 water.

3. In combination, a body having an inlet, an outlet an intermediate partition with an opening, a valve casing screwed into said body and having a valve chamber in its inner end, and a contracted bore above the 50 valve chamber and a lateral perforation connecting this bore with the inlet, the lower end of said casing being water tightly seated against the said partition; with a valve in said chamber depending through the 55 opening in the partition, and adapted to be closed by the water pressure and seat against the upper end of said chamber, a guide pin attached to the said valve and entering the bore of the casing, means engaging said pin to limit the opening movement of the valve, and a threaded spindle attached in said casing adapted to engage said guide pin and 60 open the valve.

In testimony whereof I have signed my 70 name to this specification in the presence of two subscribing witnesses.

GEORG MÜLLER.
